UNITED STATES PATENT OFFICE.

RUSSELL F. TUCK, OF LONG BEACH, CALIFORNIA, ASSIGNOR OF ONE-HALF TO PAUL G. ROHWER, OF LONG BEACH, CALIFORNIA.

ROD ELEVATOR.

Application filed May 7, 1928. Serial No. 275,741.

This invention relates to an elevator for rods, tubing, and the like, and is used in the placing or removing of the rods or tubing in oil or water wells.

- 5 An object of my invention is to provide an elevator in which the latches are so arranged that the weight of the rods thereon will tend to hold the latches in closed position.
- 10 A further object is to so position the latches of an elevator that they will provide a bearing surface for the tubing post against which the elevator bears.

15 Another object is to provide an elevator in which the rods are easily latched and from which they may be readily removed.

An advantage of my elevator resides in the fact that the rods cannot readily be accidentally removed therefrom, nor will the 20 latches open to permit the elevator to slip off of the rods.

Other objects, advantages, and features of invention may appear from the accompanying drawing, the subjoined detailed description, and the appended claims.

In the drawing:

Fig. 1 is a side elevation of the elevator.

Fig. 2 is an end view of the same.

Fig. 3 is a plan view.

30 Fig. 4 is a sectional view taken on line 4, 4 of Fig. 3.

Fig. 5 is a perspective view of one of the latches.

Referring more particularly to the drawing, the numeral 1 indicates the substantially rectangular elevator body from the sides of which trunnions 2, 2 extend. A bail 3 is pivotally secured to the trunnions 2 and provides a means by which the elevator is raised or lowered as the sucker rods, or the like, are inserted or removed from the well. The trunnions 2 are preferably above the center of gravity of the body 1 so that the elevator will normally hang in 45 in the position shown in Figures 1 and 2.

A vertical bore 4 extends through the body 1 and is of an appropriate size to receive the sucker rod 5. A slot 6 is cut through the body 1 and extends from the 50 forward edge thereof to the bore 4. Thus it will be seen that the rods are inserted in the elevator by inserting them through the slot 6 until they rest in the bore 4.

To prevent the rods from falling out of 55 the elevator and effectively latching them in

position, I provide a pair of pivotally mounted latches 7, 8, which latches extend across the slot 6 to prevent removal of the rods. The upper surfaces of the latches 7, 8 coincide with the surface of the body 1. 60 Thus when the rods are in position, as shown in Figures 1 and 2, the box 9 of the rods will bear against the latches, effectively preventing them from accidentally opening, and also providing a bearing surface about the 65 entire circumference of the rod.

Angularly extending cuts 10, 11 extend through the body 1 from the slot 6 to the outer edges. The latches 7, 8 are mounted in the cuts 10, 11, respectively, and are secured against movement by angularly extending pivot pins 12, 13, respectively. Thus it will be seen that the latches in opening or closing move in a plane at an angle to the upper surface of the body 1. 75

The latches 7, 8 are each provided with a side plate 14, 15, respectively, which extends downwardly along the side of the body 1, and openings 16, 17 are provided to permit inward movement of the side plates. 80 A coil spring 18, 19 is provided between the side plates 14, 15, respectively, and the inner wall of the openings 16, 17. These springs serve to urge the side plates outwardly and thus swing the latches 7, 8 into closed position. The springs extend over pins 20, 20 on the side plates 14, 15, thus holding the 85 springs against movement.

When it is desired to unlatch the elevator the operator grasps the two side plates 14, 15, pressing them inwardly, and this swings the latches 7, 8, upwardly and outwardly until a free passage is left through the slot 6 through which the rods are pulled. Due to this upward and outward motion of the 95 latches it will be evident that any pressure on the top thereof will effectively prevent them from moving and will hold the rods against accidental removal from the elevator.

On both sides of the body 1 I provide a pair of pins 21, 22, these pins serving the purpose of limiting the swing of the bail 3 so that the body 1 can never be accidentally turned upside down.

Having described my invention, I claim:

1. A rod elevator comprising a body, trunnions on the body, a bail pivotally secured to the trunnions, said body having a vertical bore therethrough, and a slot ex- 110

tending to said bore through which the rods are inserted, a pair of latches pivotally mounted in the body, said latches extending across the slot when in closed position, said latches being adapted to swing upwardly and outwardly to unlatching position.

2. A rod elevator comprising a body, trunnions on the body, a bail pivotally secured to the trunnions, said body having a vertical bore therethrough, and a slot extending to said bore through which the rods are inserted, a pair of latches pivotally mounted in the body, said latches extending across the slot when in closed position, said latches being adapted to swing upwardly and outwardly to unlatching position, and the upper surfaces of said latches coinciding with the upper surface of the body when said latches are in closed position.
3. A rod elevator comprising a body having a central bore therein, and a slot communicating therewith, a pair of cuts extending from the slot to the side edges of the body and inclined upwardly at an angle, a latch pivotally mounted in each of the cuts, said latches extending across the slot when in closed position.

4. A rod elevator comprising a body having a central bore therein, and a slot communicating therewith, a pair of cuts extending from the slot to the side edges of the body and inclined upwardly at an angle, a latch pivotally mounted in each of the cuts, said latches extending across the slot when in closed position, and spring means urging said latches into closed position, the upper surfaces of said latches coinciding with the upper surface of the body.

5. A rod elevator comprising a body having a central bore therein, and a slot communicating therewith, a pair of cuts extending from the slot to the side edges of the body and inclined upwardly at an angle, a latch pivotally mounted in each of the cuts, said latches extending across the slot when in closed position, side plates formed on said latches, and a spring positioned between each side plate and the body whereby the latches are urged into closed position.

6. A rod elevator comprising a body having a central bore therein, and a slot com-

municating therewith, a pair of cuts extending from the slot to the side edges of the body and inclined upwardly at an angle, a latch pivotally mounted in each of the cuts, said latches extending across the slot when in closed position, said body having openings in the front face thereof, side plates on the latches adapted to fit into said openings, said openings being so adapted and arranged that the side plates can move inwardly to swing the latches upwardly and outwardly into unlatched position.

7. A rod elevator comprising a body having a central bore therein, and a slot communicating therewith, a pair of cuts extending from the slot to the side edges of the body and inclined upwardly at an angle, a latch pivotally mounted in each of the cuts, said latches extending across the slot when in closed position, said body having openings in the front face thereof, side plates on the latches adapted to fit into said openings, said openings being so adapted and arranged that the side plates can move inwardly to swing the latches upwardly and outwardly into unlatched position, and a spring adapted to bear against each of the side plates, said spring being positioned within the opening.

8. A rod elevator comprising a body having a central bore therein, and a slot communicating therewith, a pair of cuts extending from the slot to the side edges of the body and inclined upwardly at an angle, a latch pivotally mounted in each of the cuts, said latches extending across the slot when in closed position, said body having openings in the front face thereof, side plates on the latches adapted to fit into said openings, said openings being so adapted and arranged that the side plates can move inwardly to swing the latches upwardly and outwardly into unlatched position, and a spring adapted to bear against each of the side plates, said spring being positioned within the opening, and the upper surfaces of said latches coinciding with the upper surface of the body.

In testimony whereof, I affix my signature.

RUSSELL F. TUCK.
